United States Patent Office

Des. 197,050

Patented Dec. 10, 1963

197,050

DOOR HANDLE

Hy Orenstein, 520 E. 21st St., Brooklyn, N.Y.

Filed June 14, 1962, Ser. No. 70,555

Term of patent 14 years

(Cl. D10—8)

FIG-1

FIG-3

FIG. 1 is a side elevational view of a door handle, showing my new design;

FIG. 2 is a front elevational view; and

FIG. 3 is a rear elevational view thereof.

I claim:

The ornamental design for a door handle, substantially as shown.
